UNITED STATES PATENT OFFICE.

THOMAS KELLER, OF MINNEAPOLIS, MINNESOTA.

WRENCH.

Application filed February 23, 1922. Serial No. 538,568.

To all whom it may concern:

Be it known that I, THOMAS KELLER, a citizen of the United States, residing at Minneapolis, in the county of Hennepin and 5 State of Minnesota, have invented certain new and useful Improvements in Wrenches; and I do hereby declare the following to be a full, clear, and exact description of the invention, such as will enable others skilled 10 in the art to which it appertains to make and use the same.

This invention relates to a wrench of well known form having a fixed and a movable jaw and in which the handle portion, which 15 is usually integral with the fixed jaw, extends at an acute angle to both the operative faces of the jaws and to the line of movement of the movable jaw. Such wrenches are provided with adjusting means for moving 20 the movable jaw and there is usually some play or lost motion between the movable jaw and the fixed parts of the wrench. The movement or vibration of the movable jaw, due to this lost motion, results in 25 a change of position of said movable jaw. Thus, when the wrench is picked up and laid down several times by a workman the movable jaw will have made an appreciable movement and will have to be re-adjusted.

30 It is an object of this invention, therefore, to provide such a wrench with simple and efficient means for preventing the play or movement of the movable jaw except when caused by the adjusting means.

35 It is more specifically an object of the invention to provide the movable jaw at its inner end with a yielding and slidable device tending to hold it firmly in position.

These and other objects and advantages 40 of the invention will be fully set forth in the following description made in connection with the accompanying drawings in which like reference characters refer to the same parts throughout the different views, 45 and in which,

Fig. 1 is a view showing the operative parts of the wrench in central longitudinal section and showing the handle in side elevation;

50 Fig. 2 is a view in front elevation of the wrench, as seen from the left of Fig. 1; and

Fig. 3 is a vertical section taken on the line 3—3 of Fig. 1, shown on an enlarged scale.

55 Referring to the drawings, a well known and much used type of wrench is illustrated

comprising a handle member 1 having integral therewith a head portion 2, which head portion comprises a fixed jaw 3. The head portion 2 has formed therein a transversely extending channel 4 which is semi-cylindrical in shape and has extending from its upper portion, a slot 5 having parallel side walls. A movable jaw 6 is provided and has its inner or lower portion formed to fit the semi-cylindrical channel 4 and also formed with a contracted narrow portion moving in the slot 5. The sides of the jaw members are usually rounded, as shown, and the slot 5 is extended to form an undercut portion of the fixed jaw 3 into which projects an extended part 7 of the movable jaw 6. The bottom or inner portion of the movable jaw 6 is provided with rack teeth which are adapted to be engaged by the threads of a cylindrical threaded member 8 disposed in a recess formed in the head 2 and journaled on a pin 9 threaded into the head at its inner end and provided with a slot at its outer end by which it may be removed, this pin occupying a recess formed in the head 2.

With the construction described, the jaw 6 tends to fulcrum about the screw 8 and have a slight play in the head 2. To prevent this, the inner part of the jaw 6 is provided on its surface adjacent the bottom of the channel 4 with a small cylindrical recess in which are disposed a compression spring 10 and a ball 11. The latter is 50 pressed out against the bottom of channel 4 and the spring 10 thus acts to keep the inner part of the movable jaw 6 pressed upwardly in contact with the top of the channel 4. When the movable jaw 6 is adjusted by the screw 8 the ball moves along the bottom of the shell 4 with substantially no friction.

With the described structure, as previously stated, the jaw 6 will remain firmly in its adjusted position. Handling of the wrench will thus not result in vibration and movement of said jaw so as to cause repeated adjustments thereof. The spring 10 and ball 11 act in the manner described to 100 keep the outer portion of the jaw 6 in its farthest position from jaw 3. The wrench is thus always held with its jaws in the wide open position to which they have been adjusted. This is a desirable result of the 105 elimination of the loose movement of the movable jaw.

It is thus seen that applicant has provided a very simple and efficient improvement on this type of wrench and one that will add greatly to the utility thereof. The 5 applicant has had much experience with this type of wrench and the present improvement has been found to have great utility and efficiency in actual practice.

It will, of course, be understood that 10 various changes may be made in the form, arrangement and proportions of the parts without departing from the scope of applicant's invention, which, generally stated, consists in the matter shown and described 15 and set forth in the appended claims.

What is claimed is:

1. A wrench having a handle portion and a head portion rigid therewith comprising a fixed jaw, the operative face of which 20 makes an acute angle with the longitudinal axis of said handle portion, said head portion having a channel formed therein extending substantially normal to the face of the fixed jaw, a movable jaw having a 25 portion shaped to substantially fit said channel to slide therein, said movable jaw having a recess formed in its inner portion in the surface adjacent the bottom of said channel, a spring pressed ball in said recess 30 adapted to bear on the bottom of said channel and hold the inner part of said movable jaw pressed outwardly against the top of said recess to prevent vibration of said movable jaw, and means for adjusting said 35 movable jaw.

2. A wrench comprising a handle having a head portion at one end carrying a fixed jaw thereon, said jaw having a face extending at an acute angle to the center 40 line of said handle, the channel in said head extending normal to said fixed jaw, a movable jaw having a portion fitting in and movable in said channel and having rack

teeth on its inner side, a spring-pressed ball in said movable jaw engaging the bottom of 45 said channel, and means in said head portion engaging said threads to traverse the movable jaw.

3. The structure set forth in claim 1, said channel having a narrow extension at its 50 outer side having parallel walls, said extension projecting under said fixed jaw to form an undercut recess therein, and said movable jaw having its inner side projecting into said undercut recess. 55

4. The combination with a wrench having a fixed and movable jaw with a handle extending from the fixed jaw, said movable jaw having teeth moving adjacent a surface in said fixed jaw, said fixed 60 jaw having a portion above said surface against which the movable jaw may engage, means engaging said teeth to move said jaw, said movable jaw having a recess adjacent the inner end of the portion moving adjacent said surface, and a spring pressed member in said recess engaging and moving on said surface to hold the movable jaw against lost motion and creeping.

5. A wrench comprising a handle portion with a head portion and a fixed outer jaw rigid therewith, said head having a groove therein extending substantially normal to the face of said fixed jaw, and a movable jaw slidable in said groove, teeth 75 on said movable jaw adjacent the bottom of said groove, means in said head engaging said teeth, said last mentioned jaw having a recess therein, and a spring pressed member disposed in said recess adjacent the 80 inner side of the jaw to engage the bottom of said groove and to hold said movable jaw in position to prevent lost motion and creeping thereof.

In testimony whereof I affix my signature. 85
THOMAS KELLER.
